UNITED STATES PATENT OFFICE.

HAROLD A. WELCOME, OF LOWELL, MASSACHUSETTS, ASSIGNOR TO AMERICAN MASON SAFETY TREAD COMPANY, OF LOWELL, MASSACHUSETTS, A CORPORATION.

STAIR TREAD.

Application filed March 6, 1924. Serial No. 697,357.

To all whom it may concern:

Be it known that I, HAROLD A. WELCOME, a citizen of the United States, residing at Lowell, in the county of Middlesex and State of Massachusetts, have invented certain new and useful Improvements in Stair Treads, of which the following is a specification.

This invention relates to safety treads on non-slipping treads such as are desirable for use on stairways, bus and car steps and other places where there is danger of persons slipping and where there is excessive wear.

My purpose is to provide a cheap, tough tread which can be readily transported and attached without being injured, and which has a flat top surface the whole face of which is of non-slipping material, and which has a front edge or nosing which is tough and durable and of which a substantial part is composed of non-slipping material so that it will not break, will wear a long time and will also prevent slipping.

Broadly speaking my invention includes a sheet metal base plate covered with an integral sheet of non-slipping material which is locked to the base plate and which extends right out to the front edge, or what will be the front edge when in use.

With my construction, the front edge of the base plate can be bent down so as to conform to any size or shape of the support, such as a stair tread or a platform of any kind on which it rests.

I am aware that treads formed of metal with parallel channels filled with lead as shown in patent to Mason, No. 481,702, Beevers, No. 800,895, and Farmer, 838,247, have been used and in the latter, locking tongues have been used.

I am also aware that a tread including a tough metal base with locking lips to hold a lead surface which extends over the nosing is shown in patent to Messick No. 1,094,859.

In association with a sheet metal base having locking members which hold in place a non-slipping composition which extends with a smooth top over the whole of the base, I claim to be the first to use a plurality of similar integral spaced front lugs which extend upwardly and backwardly from a downwardly bent edging or nosing, the spaces between the lugs being filled with the anti-slipping composition.

Fig. 1 is a section on line 1--1 of Fig. 2

showing the base plate before it is filled with composition.

Fig. 2 is a plan view of Fig. 1.

Fig. 3 is a section on line 3--3 of Fig. 4 showing the base plate filled with composition.

Fig. 4 is a bottom view of Fig. 3.

Fig. 5 is a sectional perspective showing a complete stair tread in place with the riser and regular tread.

Fig. 6 is a perspective of a modified form of stair tread in which the back edge is not bent up and instead of lugs, a strip of crimped metal is spot-welded to the base.

Fig. 7 is a detail in perspective showing a base with no lugs nor expanded metal, and at the front, spaced angular lugs riveted to the base instead of being integral therewith.

Fig. 8 is a perspective view showing a form of tread which is convenient for shipping and serves the desired purpose in most cases.

Fig. 9 is a sectional perspective of a modified type of front lugs.

In the drawings, A represents a plate of sheet metal having an upwardly bent back edge 14 and a plurality of locking lugs 10 and 11, pressed upwardly from the main flat portion 9 of the base leaving hole 7, 7, and 13, represents a downwardly bent front edge upwardly and backwardly from which extend the integral spaced front lugs 12, 12, punched upward from the plate A leaving holes 8, 8.

B represents the anti-slipping composition which is preferably applied to the plate in a plastic condition and troweled or pressed down so as to fill the holes 7, 7, from which the lugs 10, 11, have been pressed, and covering the locking lugs 10 and 11 extending into holes 8, 8, and preferably flush or a little over the top faces of the front lugs 12, 12 and at 15, 15, between and flush with, or slightly in advance of the front and top faces thereof.

In Fig. 5, F represents the riser and G the wooden tread having a front edge 18, which fits the bent down front edge 13 of plate A.

The back edge 14 may be at right angles and fit snugly against the next riser H or there may be a space between, as shown at 76 in Fig. 8.

In Fig. 6, I show a plate L without locking lugs and with no bent up back edge but with the bent down front edge 45, and the

upwardly bent front lugs 43, 43, punched out from the holes 47, whereby there are spaces 44, between the lugs 43, 43.

Instead of locking lugs, I show crimped metal M, spot-welded at 40 to the base plate 42. This metal M serves to lock the anti-slipping composition in place.

In Fig. 7, the base O has its front edge bent down at 61 but its back edge is not bent up and there is no locking means for the anti-slipping composition.

Instead of integral front lugs I show the spaced upwardly bent front lugs 52 which are attached by rivets 53, or spot welding 54, to the base plate 50.

In Fig. 8, I show an anti-slipping tread which preferably has front lugs like 12, 43 or 52, but which do not show, attached to a wooden tread G of larger size leaving a space 76 at the back and a space 77 at each end.

In this case, the base R has a bottom plate 70 from which a back edge 71 is bent up and at each end, a side edge such as 72 is bent up. The back edge 71, side edges 72, 72, and front lugs inclose the composition B and protect its edges when the tread is being shipped and also when it is in use on a larger wooden tread.

For locking members, I show expanded metal 73, the meshes of which are spot-welded as at 75, 75 to bottom or base plate 70.

While a sheet metal base is desirable, it is

clear that any kind of metal base may be used.

It is also clear that the downwardly bent front edge such as 13 or 61 may be omitted and teeth such as 81, 81, may be cut and bent up at right angles from base 80 as shown in Fig. 9.

My preferred type of tread is made of sheet metal bent up at the back and sides to form a pan, and having at the front spaced integral lugs or teeth bent up from the bottom, such pan being filled with a non-slipping artificial stone compound which is locked to the bottom of the pan, either by lugs bent up therefrom, or other suitable metal anchoring means such as expanded metal spot-welded thereto, with the top surface smooth and substantially level with the top of the back and side edges and extending between and over the lugs.

Preferably these lugs are bent over back so that the material extends under them and is thereby held in place.

I claim:

In a stair tread, the combination of a sheet metal base having locking members, and a front edge from which integral spaced front lugs extend upwardly; with a non-slipping composition which covers the locking members and extends with a smooth top over the whole of the base and between the front and top faces of the front lugs.

HAROLD A. WELCOME.
